SURFACE DECORATING METHOD AND APPARATUS

Howard F. Gundlach, Cleveland, Ohio, assignor to Oxford Varnish Corporation, Detroit, Mich., a corporation of Michigan

Application December 15, 1937, Serial No. 179,954

15 Claims. (Cl. 101—35)

This invention relates to a surface decorating apparatus, and especially to an improved form of apparatus for transferring a pattern to workpieces, the surface contours of which deviate from a common plane. This, therefore, is the general object of the present invention.

Another object of the present invention is the provision of the work decorating apparatus, in which a pattern is transferred with a high degree of accuracy from a substantially planar or cylindrical pattern surface to a workpiece, having a surface contour differing from the surface contour of a pattern.

A further object of this invention is to provide a work decorating transfer member, which will cooperate with a pattern surface and a workpiece, in such a manner that the pressure between the member and either the pattern or workpiece may be regulated without regard to the deviations in surface contour of the workpiece from that of the pattern.

A more specific object of this invention is to provide a transfer roll, the surface of which may be positively brought into a true cylindrical form, or which may be positively deformed, prior to the application of the roll to either the pattern or the work, and which cylindrical or deformed conditions may be positively maintained while the roll is engaging the pattern or work.

Another object of the present invention is to provide a transfer roll, a predetermined surface area of which may be positively deformed, and which deformed area will extend circumferentially of the roll a distance less than the entire circumference, and wherein those portions of the roll surface which are not deformed will remain in a true cylindrical formation.

Other objects and features of the present invention will become apparent from the following description relating to the accompanying drawings, which illustrate preferred forms of my invention. The essential features of the invention will be set forth in the claims.

In the drawings, Fig. 1 is a plan view of a decorating apparatus, in which my invention is incorporated; Fig. 2 is a substantially vertical section of the apparatus, as indicated by the lines 2—2 on Fig. 1; Fig. 3 is a transverse vertical section, as indicated by the lines 3—3 on Fig. 1; Fig. 4 is an enlarged vertical section through the transfer member, the plane of the section being indicated by the lines 4—4 on Fig. 3; Fig. 5 is a section similar to Fig. 4, but illustrating the transfer roll in a true cylindrical form; Fig. 6 is a view, similar to Fig. 4, illustrating a modi-

fied form of roll, adapted for use in the decoration of workpieces having a portion thereof raised out of the general plane of the work, rather than a portion depressed from such plane; Fig. 7 is a section similar to Fig. 3, and illustrating a modified form of roll, adapted for use in connection with a workpiece, which varies irregularly from the general plane thereof; Fig. 8 is a vertical section of the transfer roll illustrated in Fig. 7; and Fig. 9 is a sectional view, similar to Fig. 8, but illustrating the transfer member in a true cylindrical condition.

Referring in detail to the drawings, it will be seen that there is provided a decorating apparatus comprising a table or frame 10, in the nature of an inverted box. Adjacent one end, the frame 10, there is provided a mounting 11, adapted and arranged to support a pattern or printing plate 12, in spaced relationship and substantially horizontal alignment with a workpiece W. The workpiece W is removably mounted at the other end of the table by a support 14. The upper surfaces of side walls 15 of the table 10 are provided with racks 16, which coact with respective gears 17 of a transfer roll 20, and maintain the transfer roll in joint registration with the pattern and workpiece. The roll 20 is also provided with a pair of discs 18, which engage rails 19 carried by the table walls 15, thus limiting the pressure between the roll 20 and the pattern and workpiece.

The apparatus above described is well adapted to use a photo-engraved plate as a pattern. When such a plate is used, color, for instance a printing ink, is applied to such plate and the excess color removed in a manner well known in the intaglio printing arts. The transfer or offset roll 20 is then placed on the pattern and rolled thereacross, thus the design in color is transferred from the pattern to the transfer coating 21 of the roll. The roll is then progressed along the rails 19 and brought into engagement with the workpieces W, whereupon the design is transferred from the roll to such workpieces. The roll is then removed from the apparatus and cleansed to prepare it for another cycle of operation.

It will be noted from Fig. 1 that the pattern there shown is a smooth planar plate. The workpieces, however, as indicated in Figs. 1 and 2, have depressions W1 formed therein. In the past it has been found difficult to accurately transfer a design from a planar printing plate to such a deformed workpiece. Various devices and mechanisms have been provided, some of which are more or less successful, such as, for instance, that shown in my copending applications, Serial

No. 113,406, filed November 30, 1936, and Serial No. 155,644, filed July 26, 1937.

Generally such devices have been such that the change in the form of the roll was dependent upon the amount of pressure used in maintaining the roll in contact with either the pattern or printing plate. For some types of decoration this pressure is not critical. However, in certain types of decorations, such as the application of designs which simulate fine woods, this pressure should be maintained at the minimum required to transfer the color to and from the transfer roll. Indeed, great care is taken in the development and manufacture of the transfer material to provide a transfer surface which requires a minimum amount of pressure to effect the transfer.

When the printing pressure is utilized to change the shape of the roll, the pressure between the roll and the workpiece is either unbalanced or the pressure required to change the form of roll is greater than that required to effect the transfer. When the designs being transferred include comparatively fine details, lines, dots, etc., excessive or unbalanced printing pressures cause a blurring of certain portions of the design and a loss of sharpness and accuracy of the detail.

The transfer mechanism of the present invention overcomes the foregoing disadvantages by providing a transfer member, the predetermined form of which is changed entirely independently of the printing pressures, and such printing pressures are positively limited while at the same time the roll is maintained in an irregular shape which will conform to the irregularly shaped surface to be printed.

As heretofore mentioned, the transfer roll is provided with a pair of discs 18, which travel along tracks 19 on the frame 10. The pattern and work supports are arranged to be adjusted vertically by supporting wedges 13, such wedges being shown in Fig. 3. Any suitable means (not shown) may be provided to move these wedges, relative to each other, and maintain them in an adjusted position. This arrangement of supports for the pattern, the work and the transfer roll enables the relative adjustment of these members to permit the pressure of the roll on either the pattern or the work to be considerably less than the weight of the roll, and, in fact, less than the pressure required to distort the transfer material of the roll an amount sufficient to cause it to simultaneously engage the low and high surfaces of the work W1 and W2, respectively.

The transfer member comprises a roll having a coating of flexible or distortable transfer material, and is provided with mechanism which positively distorts this material and positively returns it to its original condition without in any way affecting the printing pressure, and in such a manner that a predetermined printing pressure may be maintained with all points of the pattern and with both high and low areas of the workpiece. Obviously, the pressure between the roll and the pattern may differ from the pressure between the roll and the work, if such becomes desirable, because of the relative natures of the respective surfaces.

The transfer roll, as shown in Figs. 3 to 6, inclusive, comprises a hollow cylinder 21, having suitable end members 22, to which the gears 17 and discs 18 are secured. The wall of this cylinder is provided with an opening 29, which is substantially the same area as the area of the depressed portions W1 of the workpiece, or, as shown in the drawings, this area may be sub-

stantially the same as the depressed portions of two workpieces, thus enabling a plurality of workpieces to be simultaneously decorated.

The opening 29 in the cylinder 21 is normally closed by a movable segment 26. This segment 26, as shown in Figs. 4 and 5, is movable bodily toward and away from the periphery of the roll, being slidably mounted between a pair of guide-way members 27, formed internally of the cylinder 21. This segment is provided with a hollow boss portion 28, which extends inwardly beyond the axial center of the roll, and through which a shaft 30 extends.

The shaft 30 is rotatably mounted in end members 22 of the roll and is provided with a pair of cams 31, arranged to engage wearing pads 32 of the hollow boss of the segment. These cams 31 are so arranged that consequent upon the rotation of the shaft 30 through, for instance, an angle of one hundred and eighty degrees, the extension 26 is moved outwardly from the position shown in Fig. 4 to the position shown in Fig. 5, or vice versa. It will be noted that when in the position shown in Fig. 5, the exterior surface of the segment 26 forms a continuation of the cylindrical surface of the cylinder 21, and causes the transfer material, which envelops the roll, to assume a true cylindrical shape, whereas, when the shaft has been rotated to move the segment outwardly, the transfer material supported by the segment is pressed or deformed outwardly beyond the normal circumference of the roll. The amount of this extension is such that the distended surface of the transfer material will extend into the depression W1 of the workpiece and engage such surface with substantially the same as the surface pressure between other portions of the roll surface and the high portions W2 of the work surface. Thus the roll may be moved across the workpiece with a minimum amount of contacting pressure, inasmuch as the distortion of the roll is accomplished entirely mechanically by positively distorting the base cylinder on which the roll is mounted, and in no way depends upon the pressure between the roll and the workpiece. The decoration of the workpiece is thereby accomplished with a minimum amount of distortion.

To further avoid the distortion of the design, due to the elongation of the roll, and especially the elongation of the transfer material, which I have found takes place to a great extent only at points opposite the junction between the cylinder 21 and the segment 26, I find it convenient to exaggerate or compress the lines of the pattern 12, particularly as indicated at 12a on Fig. 1, so that when the roll is distended, as shown in Fig. 4, these lines will be transferred to the pattern in substantially the same spacing as the lines on other or non-distended portions of the roll. This may be accomplished, in the case of wood grain patterns, by adding lines to the pattern, and by deepening such lines to enable them to be supplied with a slightly greater amount of color, thus maintaining true color and tone values.

In Figs. 1 to 5, inclusive, I have shown my apparatus as especially adapted to workpieces having a more or less regular depression formed therein. However, I also contemplate the provision of a segment 26a for the decoration of workpieces wherein the smaller surface area is raised relative to the major portion of the workpiece surface. Such a workpiece is indicated at W3 in Fig. 6. Here the segment 26a and the cam, when extended the maximum distance, cause

the surface of the segment to form a continuation of the cylindrical surface of the roll, and when the cam 31a is turned to the position shown in Fig. 6, the segment 26a is drawn inwardly, drawing with it the transfer material 25. Thus, the irregularity of the roll takes the form of a depression.

To aid in the controlling of the deformations of the roll, the rubber sleeve 24, to which the transfer material is secured, and which sleeve envelopes the roll, is such that it is in a normally stretched condition when applied thereon. Thus, if desired, the elasticity of this sleeve will maintain the gum or transfer material closely adjacent the surface of the cylinder and segment 26 or 26a. I find it desirable, under certain conditions, to secure the rubber sleeve 24 to the segment 26 and to the cylinder 21, by some suitable form of cement. Those areas of the sheath 24, adjacent the junction between the surfaces of the cylinder and the segment, may be left uncemented, thus limiting the stretching of both the gum material and elastic sheath to a point adjacent the junction of the surface of the cylinder with the surface of the segment. The distortion of the surface of the transfer material may be thus regulated and more easily compensated for in the pattern, as, for instance, by compacting the lines of the pattern heretofore described.

In Figs. 7 to 9, inclusive, I have illustrated a modified form of transfer roll, which is especially adapted for work, the surface of which varies from a common plane in an irregular manner. For instance, the variation shown in the workpiece W4 in Figs. 7 and 8, where it will be noted that these irregularities extend transversely and longitudinally of the workpiece. In this modification, the cylinder 21 is preferably formed in semi-cylindrical sections, which are bolted together by bolts 40. One of these cylindrical members is provided with a recess 41, arranged to receive a plurality of blocks 42, which may be separated by anti-friction members 44, to facilitate a free sliding movement of the blocks relative to each other, and the walls of the cylinder recess 41.

Each of the blocks 42 has secured thereto a threaded plunger or stud 45. These studs pass inward through respective guideways 46, formed in the wall of the cylinder which forms the base of the recess 41, and extends through guide openings formed in an operating block 46. The operating member 46 is slidably mounted in guideways 47 formed in the inner walls of the cylinder 21a, for movement in a direction parallel with the extent of the blocks 42.

The operating member 46 is provided with a hollow boss 49, similar to the boss 28, heretofore described, in connection with the segment 26, and through which the shaft 30 extends. The walls of the boss formation 49 cooperate with the cam members 32 in a manner similar to that heretofore described in connection with the segment 26. The studs 45 are provided with a pair of shoulders 50 and 51, between which the flanges of the operating member 46 lies. These shoulders may be provided by nuts and lock nuts, and thus adjustable relative to the studs.

This arrangement of the stud shoulders 50 and 51 is such that when the cam 31a is in the position shown in Fig. 9, the operating member 46 cooperates with the upper shoulders 50 of the studs and maintains each of the blocks 42 in its innermost position. When in their innermost

positions, the inner ends of the blocks cooperate with the base wall of the recess 41, and the outer faces of these blocks form a continuation of the surface of the cylinder 21a. When the cam is moved to the position shown in Fig. 8, the operating member 46 engages the abutments 51, forcing the blocks outwardly, as shown in Fig. 8. Obviously, the configuration of the roll shown may take any substantially desired shape, as it is possible to project each of the blocks outwardly a distance which is controlled entirely by the location of the shoulder members 51 relative to the blocks. Inasmuch as the shoulders may be adjusted, the throw of the blocks may likewise be adjusted, thus providing a roll which may be used for several different varied deformations in workpieces.

The surface contour of the roll is changed, as desired, by rotating the shaft 30 relative to the roll. As shown in the drawings, especially in Figs. 1, 2 and 3, there is secured to the shaft 30 an arm 60, which is provided with a roller 61, arranged to engage a bar 62 carried by the walls of the frame 10. As the roll 20 is moved from the pattern along the frame, the roller 61 engages the bar 62, thus arresting the rotation of the shaft 30, while continued movement of the roll rotates the latter and causes a relative rotary movement to be imparted between the roll and the shaft. The arrangement is such that this movement distends the segment 26 and distorts the roll. The bar 62 is so arranged that when the distortion is complete, the roll itself will have progressed to such a position where the roller 61 disengages the bar 62. Thereafter, the frictional contact between the cams 31 and the segment 26 or the control block 46 causes the roll 20 and the shaft 30 to rotate as a unit, thus decorating the work with the deformed roll. When the decoration of the deformed area of the work has been completed, a second roll 61a, carried by an arm 60a, which is also secured to the shaft 30, engages a second cam bar 52a, and again causes relative rotary movement between the shaft and the roll, thus returning the roll to its cylindrical form by a positive action.

From the foregoing it will be seen that my invention includes a true transfer roll and operating mechanism therefor, which roll may be positively deformed or positively brought into a true cylindrical formation, entirely independent of any pressure between the surface of the roll and the surfaces of the pattern or work. Such deformation is accomplished by means which acts from within the roll, positively distorting the surface or periphery of the roll, thus enabling the roll to be used in connection with articles of work, the surfaces of which deviate from a common plane, while using the printing pressures which are most advantageous to the transfer operations.

I claim:

1. In a work decorating mechanism, a pattern, a work support, a deformable transfer roll, means to move the transfer roll alternately into rolling contact with the pattern and with work carried by said support, means to positively restrain the roll against deformation when the roll is in contact with the pattern, and means independent of the printing pressure between the roll and the work to positively deform the roll while the roll is in contact with the work.

2. In a work decorating mechanism, a pattern, a work support, a deformable transfer roll, means

whereby the transfer roll may be brought alternately into rolling contact with the pattern and with work carried by said support, means to positively restrain the roll against deformation 5 when the roll is in contact with the pattern, means to limit the pressure between the roll and the workpiece, and means independent of the printing pressure to positively deform the roll and maintain the roll deformed while the roll is 10 in contact with the workpiece.

3. In a decorating machine having a pattern and a work support, the combination of a transfer roll, means whereby the transfer roll may be shifted alternately into rolling contact with the 15 work carried by the support and with the pattern, means to maintain a predetermined pressure between the transfer roll and the work while the roll is in contact with the work, means to positively deform the roll prior to the engagement of 20 the roll with the work, and means to maintain the deformation of the roll constant while the roll is in rolling contact with the work.

4. In a decorating machine having a pattern and a work support, the combination of a transfer 25 roll, means whereby the transfer roll may be bodily shifted alternately from rolling contact with the work carried by the support and into rolling contact with the pattern, said transfer roll having a shiftable segment, means to maintain 30 a predetermined pressure between the transfer roll and the work while the roll is in contact with the work, means to positively shift said segment prior to the engagement of the roll with the work, and means to positively shift the segment to another position subsequent to the engagement of 35 the roll with the work.

5. In a decorating machine having a pattern and a work support, the combination of a transfer roll, means whereby the transfer roll may be alternately shifted bodily from rolling contact with the 40 pattern into rolling contact with work carried by said support, said transfer roll having a shiftable segment, means to positively shift said segment to a predetermined position relative to 45 the roll prior to the engagement with work carried by said support and to maintain the segment in such predetermined position while the affected surface area of the roll is in rolling contact with the work.

50 6. In a decorating machine having a pattern and a work support, the combination of a transfer roll, means whereby the transfer roll may be alternately shifted from rolling contact with the pattern into rolling contact with the work carried by said support, said transfer roll having a shiftable segment and a sheath of resilient transfer material, means acting consequent upon the shifting of the roll to positively shift said segment to a predetermined position to deform the 55 transfer material prior to the engagement of that portion of the roll affected by such shifting with work carried by said support and maintain the segment in such predetermined position while the affected surface area of the roll is in rolling 60 contact with the work.

7. In a transfer roll having a core provided with a shiftable segment and a resilient transfer coating, means carried by the core to positively shift said segment to deform said coating prior 70 to the engagement of the affected portion of the transfer coating of the roll with a coating surface, and means to return the segment to its normal position to return the roll to a cylindrical form.

75 8. In a transfer roll, a core including a radially

shiftable segment, the circumferential dimension of said segment being less than the circumferential dimension of the core, a tubular body of transfer material enveloping said core and segment, and selectively operable means carried by 5 the roll to move said segment to either of two predetermined positions.

9. A normally cylindrical transfer roll comprising a cylindrically surfaced cone including a movable segment, the surface of which normally forms part of the surface of said core, an outer layer of flexible transfer material extending over the core and segment, a shaft extending through the core and segment and means carried by said shaft and acting on said segment to maintain the surface of said segment in circumferential alignment with the surface of the core, said last-named means also being adapted and arranged to positively move said segment to a predetermined position to move and maintain the surface of said segment out of alignment with the surface of the core. 10 15 20

10. In a transfer roll having a core including a section movable inwardly relative to the core to form a depression in said roll, such depression being less in length than the length of the roll, selectively operable means to depress and maintain depressed said section or to move said segment to a non-depressed position, as desired. 25

11. In a transfer roll having a core including a plurality of shiftable segments extending about the roll in a circumferential direction, a tubular body of transfer material enveloping said core and segments, and selectively operable means carried by the roll to move said segments to either of two predetermined positions, whereby a portion of the surface of said transfer material will be moved out of cylindrical alignment with the balance of such surface thereby positively deforming the roll to cooperate with a surface 40 45 50 55 40 to be decorated which surface has relatively raised and lowered areas.

12. In a transfer roll for decorating surfaces which deviate from a common plane a cylindrical core including a plurality of shiftable segments extending about the core in circumferential and axial direction and normally forming part of the cylindrical surface of the core, a tubular body of resilient transfer material enveloping said core and segments, and selectively operable means carried by the roll to move said segments to either of two predetermined positions to distort said transfer material from a normally cylindrical contour, and means whereby the distance of movement of said segments 55 may be adjusted relative to each other. 45 50 55

13. In a transfer roll for decorating work pieces, the surface of which deviate from a common plane, a normally cylindrical core, a sheath of resilient transfer material enveloping said core, means carried by the core to distort a portion of the transfer material, the surface area of the distorted portion extending in a circumferential direction, a distance less than the circumferential dimension of the surface of the transfer material, and in an axial direction, a distance less than the axial dimension of the surface of the transfer material. 60 65 70

14. The method of decorating a surface having an area deviating from a common plane, the length of such area being less than the length of the surface to be decorated, comprising applying color to a printing plate, the surface of which lies substantially in a common plane, and having a predetermined portion of the design 75

exaggerated, transferring such color to a cylindrical body having a resilient transfer coating by rolling contact with the pattern, so that the distorted area of the pattern is applied to a predetermined area of the transfer body, distorting such area of the body bringing the body into rolling contact with the work so that the distorted area of the body coacts with that area of the work which deviates from a common plane.

15. In a transfer roll, a core including a radially shiftable segment, the circumferential dimension of said segment being less than the circumferential dimension of the core, a tubular body of transfer material enveloping said core and segment, and means carried by the roll to move said segment to distort the roll surface.

HOWARD F. GUNDLACH.
